UNITED STATES PATENT OFFICE.

NORMAN T. DE GOLYER, OF WAUPUN, WISCONSIN.

RAILWAY-SIGNAL.

SPECIFICATION forming part of Letters Patent No. 394,466, dated December 11, 1888.

Application filed May 24, 1888. Serial No. 274,916. (No model.)

To all whom it may concern:

Be it known that I, NORMAN T. DE GOLYER, of Waupun, in the county of Dodge, and in the State of Wisconsin, have invented certain 5 new and useful Improvements in Railway-Signals; and I do hereby declare that the following is a full, clear, and exact description thereof.

My invention relates to railway-signals; and 10 it consists in certain peculiarities of construction and combination of parts, to be herein-after described with reference to the accompanying drawings, and subsequently claimed.

In the drawings, Figure 1 represents a vertical transverse section of a caboose-car having my invention applied thereto, the section being taken on line 1 1, Fig. 2; Fig. 2, a vertical longitudinal section of the same taken on line 2 2, Fig. 1; Fig. 3, a horizontal section 20 taken on line 3 3, Fig. 4; Fig. 4, a vertical section taken on line 4 4, Fig. 3, and illustrating a mechanism for partially rotating a lantern that forms part of my signal; Fig. 5, a horizontal section taken on line 5 5, Fig. 6; Fig. 6, 25 a vertical section taken on line 6 6, Fig. 5, and illustrating the construction of a lantern-support employed in my signal; Fig. 7, a plan view, partly in section, of a sprocket-gear mechanism that forms part of my invention; 30 and Fig. 8 a section taken on line 8 8, Fig. 2.

Referring by letter to the drawings, A represents an ordinary caboose-car. A vertical shaft, B, has its bearings in a bracket, C, attached to one of the car-sills, and in another 35 bracket, D, secured to an inner side of said car near its top. To the lower end of the shaft B, I attach a bevel gear-wheel, b, that meshes with a similar wheel, c, on a horizontal shaft, E, that has its bearings in brackets d 40 depending from sills of the car. Fast on the shaft E is a sprocket-wheel, F, and loosely connected to said shaft, so as to be pivotally adjustable thereon, are arms G, the outer ends of these arms being provided with bearings e for trunnions f on another sprocket-wheel, H, over which and the one F is arranged a drive-chain, I, designed to be brought in and out of engagement with a sprocket-wheel, J, on an axle, K, of the car, accordingly 45 as the arms G are raised or lowered, the axle

being provided with guards K', that prevent lateral displacement of said chain.

In order that the arms G may be readily raised or lowered, I provide each of the bearings e with an eye, g, to which I attach a yoke, 55 h, that connects with a pivoted lever, i, that has a rod-connection, j, with another lever, L, pivoted to a bracket, L', on the floor of the car, the latter lever being held in its adjusted position by means of a pin, k, passed through it and one of a series of perforations in said bracket.

Fast on the upper end of the shaft B is a bevel gear-wheel, M, that meshes with a similar wheel, N, on a shaft, O, that has its bearings on the bracket D, as illustrated in Fig. 1. Wristed to a disk, P, on the shaft O is a vertical rod, Q, that connects with a bell-crank, R, that is pivotally connected to the inner side of the turret A' of the car and has 60 a horizontal rod-connection with another bell-crank, R', pivotally connected to the turret on the opposite side of the car. Both bell-cranks have a link-connection, n, with crank-arms p on shafts S, that have their bearings q on the top of the turret A', as best illustrated in Fig. 2. Fast on the shafts S are arms T, that carry shields T', arranged to come in front and rear of signal-lanterns U U', arranged above the turret on opposite sides 70 of the latter.

The lantern U'' is fixed on a base, V, that is fast on a vertical shaft, V', that has its bearings in brackets r, projecting from the adjacent inner side of the car, and fast on this 75 shaft is an arm, s, that is connected by a link, t, with a plate, W, that is slipped onto the shaft B, to rest upon a collar, W', fast thereon.

The plate W is held in frictional contact with the collar W' by means of a spiral spring, 80 X, that surrounds the shaft B, between said plate and the bracket D, the latter being provided with depending fingers v v', as best illustrated by Fig. 4.

In the operation of my invention, when the 85 car is moving forward and the drive-chain I is in gear with the sprocket-wheel J, motion is communicated from the axle K, through bevel-gear shafts E B O, to the rod Q, and thus the bell-cranks R R' are actuated to 90 100

oscillate the shafts S, thereby causing the shields T' on the arms T to alternately show and conceal the front and rear bull's-eyes of the lanterns U U', said arms being so arranged on their respective shafts that when the car is at a standstill the light of only one lantern will be discernible, as illustrated in Fig. 1.

In practice when the car is moving forward 10 the lantern U shows a red light and the lantern U' a white light, the link t, connecting the arm s on the shaft V', being in contact with the finger v', depending from the bracket D, and when the light of one lantern is exposed 15 the light of the other will be concealed. Now, should the car be moved in an opposite direction, the rotation of shaft B will be reversed, and consequently the frictional contact of the collar W' and plate W will cause 20 the shaft V' to revolve, and thereby give the lantern U' a quarter-turn to bring the red bull's-eyes of said lantern in line with the movement of said car, the revolution of the latter shaft being limited by the finger v, depending 25 from the bracket D.

By the operation just described it will be seen that when the car is moving backward each of the two red lights will be alternately shown and concealed by the movement of the 30 shields T'.

When the car again starts on its forward movement, a reverse operation to that just described takes place, and the opposite red and white lights are again in line with the 35 movement of said car.

During the day, or at such other times when it may not be desirable to operate the signal, the lever L is actuated to raise the arms G, and thereby bring the drive-chain I out of 40 gear with the sprocket-wheel J on the car-axle K.

While I have shown and described a sprocket-gear for communicating motion from the car-axle K, it is obvious that a friction or 45 other form of gear may be used for the same purpose, and I do not wish to be understood as limiting myself to any particular style of gear by which the revolution of said shaft is accomplished, although that shown will probably 50 be the one preferred.

By the above description it will be seen that I provide a signal that will readily show, whether the car is moving or standing still, and which in the former case will indicate the 55 direction of the movement.

Having thus fully described my invention, what I claim as new, and desire to secure by Letters Patent, is—

1. The combination, with a railway-car, of 60 a signal comprising two lanterns, one of which is pivoted, crank-shafts arranged adjacent to the lanterns, a shield or shields connected to the crank-shafts, a shaft and gear mechanism, substantially as described, for oscillating 65 said shafts, whereby the light of the lanterns is alternately shown and concealed, and a

link-connection, substantially as described, for uniting the pivoted lantern with said shaft and gear mechanism, whereby a partial revolution is imparted to said pivoted lantern 70 when the car starts on its backward movement, as and for the purpose set forth.

2. A railway-signal comprising two oppositely-arranged lanterns having front and rear bull's-eyes, crank-shafts arranged adjacent to 75 the lanterns, arms connected to the shafts to come in front and rear of said lanterns, shields carried by the arms, and means, substantially as described, for rocking said shafts, as and for the purpose set forth. 80

3. The combination of a railway-car, a lantern arranged thereon, a crank-shaft arranged adjacent to the lantern, a shield or shields connected to the crank-shaft, a bevel-gear mechanism connected to said crank-shaft, a sprocket-wheel fast on an axle of the car, a drive-chain for engagement with the sprocket-wheel, and other sprocket-wheels connected to said bevel-gear mechanism and arranged to support said drive-chain, substantially as and for the purpose set forth. 85

4. The combination of a railway-car, a lantern arranged thereon, a crank-shaft arranged adjacent to the lantern, a shield or shields connected to the crank-shaft, a bevel-gear mechanism connected to said crank-shaft, a sprocket-wheel fast on an axle of the car, a sprocket-wheel connected to said bevel-gear mechanism, arms pivotally connected to said gear, another sprocket-wheel trunnioned 100 in the pivotal arms, a drive-chain carried by the last two sprocket-wheels, and a lever mechanism for actuating said arms, whereby the drive-chain is brought in and out of engagement with said sprocket-wheel on the 105 car-axle, substantially as set forth.

5. The combination of a railway-car, the lantern U', arranged outside the car, the vertical shaft V', connected to the lantern, the shaft B, having a link-connection with the one V', 110 and means, substantially as described, for actuating the latter shaft, as and for the purpose set forth.

6. The combination of a railway-car, the lantern U', arranged outside the car, the vertical shaft V', connected to the lantern, the shaft B, provided with the collar W', the loose plate W, supported by said collar, the spring X, arranged on the shaft B to exert its force against said plate, the arm s and link t, connecting 120 shaft V' and plate W, the bracket D, secured to the side of the car and provided with fingers v v', arranged to straddle said link, and means, substantially as described, for actuating said shaft B, as and for the purpose set 125 forth.

7. A railway-signal comprising a pivoted lantern provided with two lights of different colors and arranged to normally show but one color of light, a shield for alternately revealing and concealing the light, a shaft and gear mechanism, substantially as described, for

actuating the shield, and a link-connection, substantially as described, for uniting the pivoted lantern with the shaft and gear mechanism, whereby a partial revolution may be 5 imparted to said lantern to bring the other color of light into position to be alternately revealed and concealed, as and for the purpose set forth.

In testimony that I claim the foregoing I have hereunto set my hand, at Milwaukee, in 10 the county of Milwaukee and State of Wisconsin, in the presence of two witnesses.
